(57) **CLAIM**

The ornamental design for a drain trap, as shown and described.

DESCRIPTION

FIG. 1 is a perspective view of an inner part of a drain trap of my new design;

FIG. 2 is a front view of the inner part of the drain trap;

FIG. 3 is a left side view of the inner part of the drain trap;

FIG. 4 is a right side view of the inner part of the drain trap;

FIG. 5 is a rear view of the inner part of the drain trap;

FIG. 6 is a top view of the inner part of the drain trap;

FIG. 7 is a bottom view of the inner part of the drain trap;

FIG. 8 is a perspective view of an outer part of the drain trap;

FIG. 9 is a front view of the outer part of the drain trap;

FIG. 10 is a left side view of the outer part of the drain trap;

FIG. 11 is a right side view of the outer part of the drain trap;

FIG. 12 is a rear view of the outer part of the drain trap;

FIG. 13 is a top view of the outer part of the drain trap;

FIG. 14 is a bottom view of the outer part of the drain trap;

FIG. 15 is a perspective view of the drain trap shown fully assembled.

FIG. 16 is a front view of the drain trap shown fully assembled.

FIG. 17 is a left side view of the drain trap;

FIG. 18 is a right side view of the drain trap;

FIG. 19 is a rear view of the drain trap;

FIG. 20 is a top view of the drain trap; and,

FIG. 21 is a bottom view of the drain trap.

The evenly spaced broken lines depict portions of the drain trap that form no part of the claimed design. The dot dash dot broken lines denote the boundary of the claimed area and form no part thereof.

The inner part and the outer part of the drain trap are shown separately for convenience of illustration.

1 Claim, 21 Drawing Sheets
